Primary Examiner — David G Muller*Assistant Examiner* — Christina Gabrielle Cosden(74) *Attorney, Agent, or Firm* — THE WEBB LAW FIRM(57) **CLAIM**

The ornamental design for a magnetic lock, as shown and described.

DESCRIPTION

FIG. 1 is a perspective view of a magnetic lock, showing my new design;

FIG. 2 is a top view thereof, the bottom view being a mirror image of the top view;

FIG. 3 is a left side elevation view thereof;

FIG. 4 is a right side elevation view thereof;

FIG. 5 is a rear elevation view thereof; and,

FIG. 6 is a front elevation view thereof.

The portions of the magnetic lock shown in broken lines form no part of the claimed design.
